Primary Examiner — Rachel A. Voorhies*Assistant Examiner* — Benjamin D. Wannemacher(57) **CLAIM**

The ornamental design for a driveway pole with reflector, as shown and described.

DESCRIPTION

FIG. 1 is a front perspective view of a driveway pole with reflector, showing my new design;

FIG. 2 is a front view thereof;

FIG. 3 is a rear view thereof;

FIG. 4 is a left side view thereof;

FIG. 5 is a right side view thereof;

FIG. 6 is an enlarged view of the top plane;

FIG. 7 is an enlarged view of the bottom plane;

FIG. 8 is a partial enlargement of FIG. 1; and,

FIG. 9 is a folded state view thereof.

The broken lines in the drawings illustrate the portions of the driveway pole with reflector, which form no part of the claimed design.
